UNITED STATES PATENT OFFICE.

ALFRED L. SOHM, OF LOS ANGELES, CALIFORNIA, ASSIGNOR TO SOHM ELECTRIC SIGNAL & RECORDING COMPANY, OF CHICAGO, ILLINOIS, A CORPORATION OF ARIZONA.

LOCK.

1,141,215.

Specification of Letters Patent.

Patented June 1, 1915.

Application filed March 28, 1912. Serial No. 686,857.

To all whom it may concern:

Be it known that I, ALFRED L. SOHM, a citizen of the United States, residing at Los Angeles, in the county of Los Angeles and State of California, have invented a certain new and useful Improvement in Locks, of which the following is a full, clear, concise, and exact description, reference being had to the accompanying drawings, forming a part of this specification.

My invention relates to locks and more particularly it relates to that type of locks which involve the simultaneous and accurate positioning, longitudinal of the axis of the key, of a plurality of wards, the idea being that these wards can then be rotated in interior annular grooves. By means of the key, these wards are moved into their respective proper places against the tension of springs and all of the wards must be held in just exactly their respective positions at the same time in order that the movable element of the lock may be free to operate, and this makes it practically impossible to pick the lock or to open it in any way except by means of an authorized key. There are other features which I employ to eliminate any possibility of picking and, as a final precaution, I provide an auxiliary feature which is really a lock in itself. The combination of this auxiliary feature and the main features of the lock is important, however, since it insists upon a certain combination in the structure of the key and this emphasizes the difficulty of unauthorized duplication.

Broadly, it is the idea of my invention to employ a stationary element and a rotary element and to provide one of said elements with a plurality of annular grooves and the other of said elements with a plurality of longitudinally movable wards. The insertion of the key positions these wards with respect to the grooves and it becomes possible to turn the rotary element relative to the stationary element. The wards may be made of different thicknesses and different heights, and the grooves may be made of different widths and different depths and in this way the number of combinations for different locks is indefinitely multiplied and the difficulty of unauthorized reproduction is infinitely increased. The rotary element of the lock, of course, carries the bolt-thrower and it is a feature of my invention

that this bolt-thrower is normally in an inoperative position and can be brought into an operative position only by the insertion of the proper key. The two positions of the bolt-thrower may, of course, be used to advantage and I therefore make it part of some of the appended claims.

My invention is embodied in the device illustrated in the accompanying drawings, in which—

Figure 1 is a side elevational view thereof, showing the key inserted; Fig. 2 is a longitudinal vertical sectional view thereof, showing the key inserted; Fig. 3 is a side elevational view of the key; Fig. 4 is a cross-sectional view thereof taken on the line 4—4 of Fig. 2 and looking in the direction indicated by the arrows; Fig. 5 is an end view of the lock; and Fig. 6 is a perspective view of one of the wards.

Like reference characters are applied to the same parts throughout the various figures.

The stationary element, which is adapted to be set firmly in a door, is in the form of a barrel 7 which has firmly secured on the inside thereof, the two oppositely disposed partial annuli 8, 8. In a suitable co-axial pocket in the front end of the barrel 7 and the annuli 8 a disk 9 is rotatably mounted, this disk being provided with a peripheral groove 10 into which the ends of the screws 11, 11, engaging in the barrel and the annuli, extend, the front ends of the annuli being bridged by pieces 12, 12 to provide for the pocket referred to and the reception of the screws. It will be noted that these screws, when the parts are in position, have their heads flush with the periphery of the barrel 7 and that when the barrel is disposed properly in a door, these screws are inaccessible and hidden.

Disposed in a co-axial pocket at the rear end of the barrel is a disk 13 which is rotatable and which is connected with the disk 9 by means of a plurality of tubes 14, 14, in this case four in number. The disks 9 and 13 and the tubes 14, 14, form the rotatable element of the lock, and operate as a unit. The axes of the tubes 14, 14 are arranged circularly about the axis of the barrel and the key, as will be described later, is adapted to pass between the tubes as illustrated in Fig. 4, there being two tubes on one side of the key and two on the other side, as shown.

Each of the tubes 14 is provided with a longitudinal slot 15, extending practically in the entire length thereof, and this provides for the accommodation in the tube of the carrier 16 from which the ward 17 extends. The carrier 16 is in the form of a small rod and fits snugly within the tube. The ward 17, which is preferably integral with the part 16, extends out of the tube through the slot 15 and passes either upwardly or downwardly as the case may be, into the corresponding space between the partial annuli 8, 8. The wards carried by the upper tubes extend upwardly and those carried by the lower tubes extend downwardly. Between each of the carriers 16 and the disk 13 a helical spring 18 is disposed and this spring tends to maintain all the carriers at the forward ends of the tubes. As will be described presently, when the key is inserted the wards are properly distributed along the length of the tube.

The annuli 8, 8 are provided with a plurality of interior annular grooves 19, 19 which are properly distributed along the axis of the annuli, one being provided for each ward. In other words, each ward has a groove of its own and when it is brought into proper position it may ride in that groove. When all the wards are in position to ride in their respective grooves, the rotary element of the lock may turn relative to the stationary element thereof and it will be clear that such operation will be impossible if any one or more of the wards are out of position. The key, which is illustrated at 20, is provided with a finger piece 21, a body 22, and a shoulder 23 separating these two parts. The body of the key is adapted to fit snugly in a slot in the disk 9 and also in a slot in the disk 13 so that the axial position of the key may be determined, and the shoulder 23 is adapted to engage the face of the disk 9 so that the longitudinal position of the key may be determined. The slot in the disk 9 is illustrated in dotted lines at 24 and this slot is supplemented at the side by a groove 25 which is adapted for the reception of a ridge 26 extending lengthwise of the key at the middle of one of the faces thereof. This determines the top and bottom position of the key.

Each face of the body of the key is provided with tables or projections 27 and the faces 28, 28 of these tables or projections are the code surfaces of the key. The ridges are in such position that their faces 28, 28 will engage the front faces of the wards 17, 17 and, against the tension of the springs 18, 18, will move them rearwardly to a certain and definite extent. As will be seen from Fig. 3, these projections or tables 27, 27 are variously distributed, that is, the faces 28, 28 lie in different cross-planes, and it will be seen that when the key is inserted to its full

extent, that is, when the shoulder 23 engages the face of the disk 9, the wards will be variously distributed along the axis of the lock. If the proper key is used, the wards will all be brought opposite their respective grooves in the annuli and, still holding the shoulder 23 against the face of the disk 9, it becomes possible to rotate the disk 13, which carries the bolt-thrower as will be pointed out, relative to the stationary element. The tension of the springs 18, 18 need not be great and there is no appreciable resistance in the insertion of the key and in holding the key fully inserted during the turning movement.

The grooves 19, 19 may all be of the same size and shape and the variations in the various blocks may be obtained by various distributions of the grooves along the length of the axis of the lock. Since there may be four, or even more, wards, and since the variations in the placements may be very small and still be ample, the possible variations are practically infinite. If desired, the slots can be made of different widths and different depths, and the wards may be correspondingly formed, so that it becomes absolutely impossible for one ward to be accommodated in any way in the slot of another ward, and this adds materially to the extreme difficulty in picking the lock. For instance, I have made the ward *a* short and thick while I have made the ward *d* comparatively long and thin, the wards *b* and *c* being of intermediate proportions. It will be apparent that such an arrangement would prevent the ward *a* from entering the slot for the ward *b*, or vice versa, and would prevent any other improper arrangement. In order to make it all the more difficult to locate the positions of the various slots I corrugate the faces 29, 29 of the annuli 8 so that a burglar, using a pick, would be unable to distinguish between the grooves thus formed and the grooves 19. For the same purpose, I round the edges of the face of the ward 17, and I provide a horizontal ridge 30 thereon so as to make the use of a hook on these wards all the more difficult. I also provide the dummy slot 19^a.

It will be seen that the degree of accuracy required may be very great and that variations in manufacture are easily produced. In order for the rotary member to turn relative to the stationary member, it is necessary that all of the wards be brought into just exactly the proper position and that they be held there against the tension of the springs during the rotary movement. Even supposing that three of the wards be brought and held in the proper position, which is quite impossible, the fourth ward will still engage one of the faces 29 of the annuli and rotation will be impossible.

The disk 13 projects beyond the rear face 13

of the barrel 7 and is provided with a diametrical dove-tail groove 31 of a depth approximately equal to the projection. A bolt-thrower 32 is in the form of a slide disposed in this dove-tail groove. The rear face of the barrel 7 is provided with an annular groove 33 and is also provided with a radial slot 34 in the plane of the axis of the dove-tail groove. A pin 35 is carried on the inner side of the slide bolt-thrower 32 and normally engages in the slot 34. It is held in this position by means of a spring 36 carried upon the disk 13 and its engagement in the slot determines the normal position 5 of the bolt-thrower. It will be noted that the key is provided at its end with a surface 37 inclined to the axis. The key is adapted to extend through a slot 38 in the bolt-thrower 32 and the surface 37 is adapted 10 to engage the face 39 of the slot 38. The slot is in such position that when the key is inserted such engagement will cause the movement of the bolt-thrower against the tension of the spring 36 to the extent of 15 moving the pin 35 from the slot 34 and bringing it into line with the annular slot 33. The parts are so proportioned that this arrangement will be assumed when the key is fully inserted and it will be seen that 20 upon rotation the pin 35 may ride in the annular slot 33. If the bolt-thrower is not properly moved by the key the pin 35 will not be moved from the slot 34 into line with the slot 33 and rotation will be impossible. 25 30 35 The normal engagement of the pin 35 in the slot 34 is thus an additional precaution and the key must therefore be provided with the proper oblique surface and length in addition to the necessity for the proper distribution of the engaging surfaces 28, 28 thereon.

I have provided a device which secures the results above enumerated without an intricate, complicated and expensive construction. The spaces between the annuli 45 may be opened to view by means of the slide parts 7^a, 7^a in the barrel 7 and in this way inspection and repair, when the device is removed from the door, is provided for. The bolt-thrower occupies two positions, one of 50 which may be made the inoperative position and the other the operative position. The operative position is attainable only when the proper key is inserted. My invention is not concerned with the bolt and I make no 55 reference thereto except to point out that the bolt-thrower and its two positions may be used in any advantageous manner.

I claim as new and desire to secure by Letters Patent:

60 1. In a lock, a stationary element, a rotatable element, and a plurality of independently restrained longitudinally movable wards carried by said rotatable element, said stationary element having a corresponding plurality of annular grooves dis-

posed side by side at irregular intervals, in which groove said wards may ride.

2. In a lock, a stationary element, a rotatable element, a plurality of independently restrained longitudinally movable 70 wards carried by said rotatable element, said stationary element having a single annular groove for each of said wards, said grooves being disposed side by side.

3. In a lock, a stationary element, a rotatable element, a plurality of independently restrained longitudinally movable 75 wards carried by said rotatable element, said stationary element having a corresponding plurality of annular grooves disposed side 80 by side at right angles to the axis of said rotatable element, in which grooves said wards may ride.

4. In a lock, a stationary element, a rotatable element, a plurality of longitudinally movable 85 wards carried by said rotatable element, said wards being distributed along the axis of said rotatable element at irregular intervals, a single annular groove for each ward in said stationary element, 90 and a spring for each ward tending to hold it out of line with its corresponding groove.

5. In a lock, a stationary element, a rotatable element, longitudinally movable 95 wards carried by said rotatable element, said stationary element having annular grooves disposed at right-angles to the axis of the rotatable element in which grooves said wards may ride, spring tending to hold said wards out of line with said grooves, and 100 a key for insertion in said rotatable part, said key having engaging surfaces along its side to encounter said wards and bring the same into line with said grooves.

6. In a lock, a stationary barrel, a rotatable disk in the front of said barrel, a rotatable disk in the rear of said barrel, a plurality of tubes connecting said disks, each of said tubes having a longitudinal slot, a spring in each tube, an interior longitudinal slot at the top of said barrel and at the bottom thereof, and a ward bearing in each tube in front of the spring therein and extending through the slot in the tube into the corresponding slot in the barrel, 110 said barrel having annular interior slots in which said wards may ride when brought into position by a key inserted through slots in said disks.

7. In a lock, a stationary member, a rotatable member, a longitudinally movable ward on one of said members, a single complete annular groove on the other of said members, in which groove said ward may ride, and means normally maintaining said 125 ward out of line with said groove.

8. In a lock, a stationary member, a rotatable member, a bolt thrower sliding diametrically in said rotatable member, a pin on said bolt thrower, there being an annular 130

groove in said stationary member in which said pin may ride when brought into line by the insertion of a key.

9. In a lock, a stationary member, a rotatable member, a bolt thrower sliding diametrically in said rotatable member, a pin on said bolt thrower, there being an annular groove in said stationary member in which said pin may ride, means for normally maintaining said pin out of line with said groove, and a key having an oblique end for engaging in a slot in said thrower to move said pin into line with said groove when brought into line by the insertion of a key.
10. In a lock, a stationary barrel, a rotatable disk in the front of said barrel, a rotatable disk in the rear of said barrel, a plurality of tubes connecting said disks, each of said tubes having a longitudinal slot, a spring in each tube, an interior longitudinal slot at the top of said barrel and at the bottom thereof, a ward bearing in each tube in front of the spring therein and extending through the slot in the tube into the corresponding slot in the barrel, said barrel having annular interior slots in which said wards may ride when brought into position by a key inserted through slots in

said disks, a bolt thrower sliding diametrically in said rotatable member, a pin on said bolt thrower, an annular groove in said stationary member in which said pin may ride, and means for normally maintaining said pin out of line with said last-named groove, the key having an oblique end for engaging in a slot in said thrower to move said pin into line with said last-named groove, said key having a shoulder to engage with the forward disk to determine its normal position.

11. In a lock, a stationary element having a longitudinal slot therein, the side of said slot being corrugated, a rotary element, a longitudinally movable ward carried by said rotatable element, said stationary element having an annular groove in which said ward may ride and having an extra annular groove.

In witness whereof, I hereunto subscribe my name this 22nd day of March, A. D., 1912.

ALFRED L. SOHM.
